AWNNG DEVICE

Charles E. Friesner, Toledo, Ohio, assignor to The Hetrick Manufacturing Company, Toledo, Ohio, a corporation of Ohio

Application October 12, 1934, Serial No. 748,006

1 Claim. (Cl. 156—15)

The primary object of the invention is to provide an awning device which is of simple, economical and rugged construction, and which is positive in action as well as relatively noiseless in operation.

A further object is to produce a new and improved awning device having the novel features of construction, arrangement and operation hereinafter described.

For purposes of illustration, but not of limitation, an embodiment of the invention is shown on the accompanying drawing, in which:

The figure is a perspective view of the awning device as mounted on a window screen frame.

The illustrated embodiment of the invention comprises a frame 10 for a screen 11, in this instance of a size suitable for a window. Mounted in the upper end of the frame are brackets 12 and 13 to receive opposite ends of an awning 15 roller 14 on which an awning 15 is adapted to be wound. The awning extends downwardly in a plane substantially parallel with the plane of the frame 10 and underneath a substantially U-shaped guide 16, which extends transversely of the frame 10 and is secured thereto. The lower end portion of the awning has a pocket 17 to receive a U-shaped supporting element 18 which is of metal, the opposite ends of which are twisted and incline upwardly to provide guide portions 19. The portions 19 are provided with elongate slots 20 respectively and are adapted to ride along guide rods 21 which are attached to the frame 10 and extend outwardly therefrom.

The twisted portions are at substantially 90° to the plane of the sides of the arms of the strip 18, and are bent at substantially the point of twisting so that their sides lie in a plane at approximately obtuse angles to the aforesaid plane. Moreover, the points of twisting are located in close juxtaposition to the inner ends of the slots to afford stub-like free terminals, with the inner ends of the slots alined with the upper side edges of the arms of the U-shape strip 18.

In order to raise or wind up the awning 15 a cord 25 has one end fixed to a sheave 22 on one end of the awning roller and extends through a guide eye 26 and then through an opening 26' to the inside of the frame where it may be secured in any suitable manner so that the awning

can be manipulated from the inside of the window. It is to be understood that by pulling on the cord 25 the frame 18 first swings about the pivots provided by the portions 20 of the frame part 18. Thereafter when the frame 18 has assumed a substantially vertical position it can move upwardly until the awning is completely wound on the roller 14. By releasing the cord 25 the weight of the frame part 18 causes it to move downwardly and swing of its own weight into the 10 desired position.

From the above description it will be seen that I have provided an exceptionally inexpensive awning device which can be readily and conveniently mounted in position of use. The parts, 15 such as the guide 16 and the frame part 18, may be of scrap metal, so that the cost is kept very low. The provision of mounting the awning on a screen frame enables the awning to be mounted in place at the same time the screen is put up, 20 thereby eliminating the trouble and annoyance heretofore experienced in putting up and taking down devices of this character.

It is to be understood that changes in details of construction, arrangement and choice of materials may be effected without departing from the spirit of the invention, especially as defined in the appended claim.

What I claim as new and desire to secure by Letters Patent is:

In an awning, a vertically disposed guide rod on each side of the awning, and an integral U-shaped metal strip set on edge and secured to the lower end of the awning, the ends of the strip being each free and twisted at about 90° and 35 bent at substantially the point of twisting so that their sides lie in a plane at substantially obtuse angles to the plane of the sides of the strip and being slotted to receive the guide rods, the points of twisting being located in close juxtaposition 40 to the inner ends of the slots to provide stub-like free terminals with the inner ends of the slots alined with the upper side edges of the arms of the U-shaped strip so that in movement to closed position the arms of the U-shaped strip will lie 45 closely adjacent to the guide rods with their side edges confronting the rods and substantially parallel thereto.

CHARLES E. FRIESNER.
